UNITED STATES PATENT OFFICE

WILLIAM L. CHILDS, OF HOUSTON, TEXAS, ASSIGNOR TO REED ROLLER BIT COMPANY,
OF HOUSTON, TEXAS, A CORPORATION OF TEXAS

ROLLER CUTTER

Application filed March 8, 1930. Serial No. 434,219.

This invention relates to roller cutters for drill bits.

The roller bits now commonly used in the drilling of deep wells embody a plurality of

5 rotatable cutters which are usually cylindrical, conical, or frusto-conical, and are provided with external teeth which cut most efficiently when clean. No means has heretofore been provided, however, capable of keeping 10 the cutter teeth clean in drilling operations, because certain formations are encountered particles of which adhere to or are jammed into frictional engagement with the sides of the cutting teeth, to fill the spaces 15 therebetween. The necessary cutting penetration of the teeth is thereby either prevented entirely or objectionably limited.

This invention has for its object the provision of a new and improved self-cleaning 20 roller cutter.

The invention may be embodied in cutters of various shapes other than those herein shown.

Figs. 1, 2, and 3 are side, end and top plan 25 views, respectively, of a cylindrical cutter; Figs. 4 and 5 are detail fragmentary views illustrating the removal of the particles of formation from between the teeth of said cutter; Fig. 6 is a fragmentary view of a bit in 30 which said cutters may be mounted; and Fig. 7 is a fragmentary view of a bit having a conical cutter embodying the invention.

The preferred embodiment of the cylindrical cutter illustrated by Figs. 1 to 6, inclusive, 35 is provided with peripheral, axial, cutting teeth 1 and an intermediate annular groove 2 in which loosely fits the ring 3.

As the cutter rolls on the formation to be 40 cut the lower teeth 1a penetrate the same and the particles of formation moving into the annular groove 3 come into contact with the lower portion 3a of the ring, and force said ring upwardly so that its upper portion 3b is made to remove from the spaces 4 between 45 the cutters 1 the particles of formation

lodged therein. The removal of the particles of formation from the spaces 4 between the teeth 1 is illustrated quite clearly by Figs. 4 and 5.

The cutters may be mounted in any suitable manner. Fig. 6 illustrates the conventional mounting in a rotary bit head 5 having a cutter recess 5a, bearing extensions 5b and a transverse cutter pin 6.

The conical cutter 7 illustrated by Fig. 7 55 may be mounted in a conventional rotary bit head 8 and provided with a plurality of rings 9 fitting loosely in annular grooves as shown.

That a cutter so constructed will operate most efficiently will be apparent to those 60 skilled in the art.

The invention may be embodied in various forms other than that shown, and within the scope of the following claims:

I claim:

1. A roller cutter having external peripheral teeth, and a tooth cleaning ring surrounding said cutter adjacent and radially movable with respect to said teeth.

2. A roller cutter having external peripheral teeth, an annular groove adjacent said teeth, and a tooth cleaning ring fitting loosely in said groove.

3. A roller cutter having external, axial, peripheral teeth, an annular groove adjacent 75 said teeth, and a tooth cleaning ring fitting loosely in said groove.

4. A roller cutter having external, axial, peripheral teeth, an annular groove adjacent said teeth, and a tooth cleaning ring, said 80 ring fitting in said groove so that the outer edge of one side of said ring will project to a point immediately adjacent the outer edge of a tooth on the adjacent side of said roller when the other side of said ring is in contact with the bottom wall of said groove.

5. A roller cutter having external, axial, peripheral teeth, an annular groove adjacent said teeth, and a tooth cleaning ring, said 85 ring fitting in said groove so that a portion of 90

the outer edge of said ring may be moved to a point exterior of the inner parts of said teeth.

6. A roller cutter having external, axial, peripheral teeth, an annular groove between said teeth, and a tooth cleaning ring fitting loosely in said groove.

7. A roller cutter having external, axial, peripheral teeth, said teeth being longitudinally aligned, an annular groove between said teeth, and a tooth cleaning ring fitting loosely in said groove.

In testimony whereof, I hereunto affix my signature.

15 WILLIAM L. CHILDS.
